UNITED STATES PATENT OFFICE.

JOSEPH KEEFE, OF BOSTON, MASSACHUSETTS, ASSIGNOR TO THE ZEE SOCKET AND MANUFACTURING COMPANY, OF BOSTON, MASSACHUSETTS, A CORPORATION OF MASSACHUSETTS.

SOCKET-SHELL CAP AND INSULATING-LINING THEREFOR.

1,209,167.

Specification of Letters Patent. Patented Dec. 19, 1916.

Application filed September 10, 1912. Serial No. 719,556.

To all whom it may concern:

Be it known that I, JOSEPH KEEFE, a citizen of the United States, and a resident of Boston, in the county of Suffolk and State 5 of Massachusetts, have invented certain new and useful Improvements in Socket-Shell Caps and Insulating-Linings Therefor, of which the following is a specification taken in connection with the accompanying drawing, which forms a part of the same.

10 This invention relates to socket shells and insulating linings therefor.

More particularly it relates to a new and improved socket cap, and to a coöperating 15 removable insulating lining for the cap which can be readily pressed into the cap which is so formed as to securely hold it without the aid of interior projections, shoulders or other locking or securing members.

20 My invention further relates to both the improved cap and the improved insulating lining as separate articles of manufacture.

In the accompanying drawing showing 25 illustrative embodiments of my invention, and in which the same reference numerals refer to similar parts in the several figures, Figure 1 is a vertical section through my improved cap equipped with my improved 30 insulating lining; Fig. 2 is a vertical section of the cap and a side elevation of the insulating lining; Fig. 3 is a perspective view of the insulating lining.

It has been old prior to my invention to 35 use a removable insulating lining for the cap of socket shells which was held within the cap by some locking or fastening mechanism on the interior of the cap, the insulating member, or some portion of it, being 40 sprung or bent to pass over some obstruction or projection, reliance being placed upon the insulating member again springing out into its original condition to co-operate with the interior projections so as 45 to prevent the insulating lining from falling out of the cap. These insulating linings are usually made of fiber, as is well known in the art, and are usually cut away to form notches or other surfaces to 50 operate with shoulders or surfaces within the cap.

In practice, immense numbers of electric light sockets and their casings are sold to manufacturers of electric fixtures to be as-

sembled with the other portions of the fixtures made, or assembled, by such manufacturers. It is frequently necessary for such manufacturers to refinish or replate the socket casing, including the cap, to match or harmonize with the particular electric 60 fixture of which it is to be a part. Before such replating or refinishing, however, it is necessary to remove the insulating lining from the socket shell. The lower fiber lining or insulating lining, which insulates the 65 shell portion of the socket, readily slips out of the shell so that its removal does not mar it or require any particular care. The removal of the lining from the cap, however, is quite a delicate operation, for the 70 lining has to be pried off or otherwise removed from the interior locking mechanism, mounted on the interior of the cap, and which coöperates with the notches, fingers, or other portions of the insulating lining, 75 to hold it in its position within the cap. This frequently mars the insulating lining. The frequency and extent of the damage to the lining depends upon the labor employed for this purpose. Usually unskilled 80 labor is employed with the result that large numbers of the insulating linings have been either ruined by being removed from the interior locking surfaces in the cap, or have been so torn or marred that when they were 85 again placed in the cap, after it has been replated or refinished, it was liable not to retain its position and the tears or cracks in the lining caused by its removal and re-positioning would often defeat the very purpose of providing the cap with an insulation 90 to prevent it from becoming electrified with possible damage to the fixture or shock to the person who may be handling it after the fixture has been installed.

Often the interior insulating lining was 95 so torn or marred that it could not be placed back in the cap and consequently either a new lining had to be substituted or, if one was not at hand, the manufacture of the 100 entire electric light socket, or the entire fixture of which it was to form a part would have to be delayed until a new lining could be obtained. In some cases where unskilled labor was employed and speed in re-assembling the sockets after replating was demanded by the employer, no lining would be placed in some of the sockets.

2
By my invention I avoid cutting or otherwise marring the insulating lining so that there is no tendency for it to tear or otherwise become damaged or ruined by placing it originally in the cap or in removing and repositioning it to permit replating or refinishing of the cap.

In the illustrative embodiment of my invention shown in the drawings, 1 is my improved cap formed of any approved material, usually of metal, and is provided with the nipple 2 of the usual or any approved construction.

The cap is provided with the usual petticoat 3 to cover the upper edge of the socket shell (not shown). From the petticoat shoulder 4 to a point nearer the nipple 2, as for example the point 5, I provide the cap with a cylindrical portion 6 having a smooth surface on the interior of the cap and preferably also on the exterior as shown. From this cylindrical portion 6 I bend in the upper portion 7 of the cap until it engages with the nipple 2 to which it may be secured 25 by upsetting the end 8 of the nipple or the two may be secured together in any other approved manner.

My improved cap may be formed by spinning or in any other approved manner. With this cap I use a removable insulating lining 9 formed of any suitable material usually of fiber, and provide it with a cylindrical edge, the diameter of which is just a trifle greater than the internal diameter of the cylindrical portion 6 of the metal cap 1. The upper portion 11 of the insulating lining 9 is slightly convex, as shown, and provided with an opening 12 for the passage of the feed wires (not shown).

40 In Fig. 2 I have shown the removable insulating lining 9 about to be positioned within its smooth cylindrical seat 6. In pressing the lining into its seat, some slight pressure

has to be employed, for the cylindrical seat is of an appreciably smaller diameter. The 45 resiliency of the lining is such that after being once positioned it will be securely held within the cap. When, however, it is desired to remove it for any purpose, as for example to replate or refinish the cap, it is 50 merely necessary to take any blunt tool and pass it through the nipple 2 until it engages with the upper portion 11 of the lining, the opening 12 being preferably of slightly 55 smaller diameter than the opening in the nipple 2.

The withdrawal of the removable insulating lining 9 does not mar it for it is made to simply slide upon the interior cylindrical surface 6 of the shell. It can be repositioned, as previously described, without damage to itself or to the cap.

Having thus described this invention in connection with several illustrative embodiments thereof to the details of which I do 65 not desire to be limited, what is claimed as new and what it is desired to secure by Letters Patent is set forth in the appended claim.

An insulating lining for socket shell caps 70 and the like, said lining having a convex or dome-shaped upper portion and a cylindrical flange whereby, when said lining is inserted in a socket shell cap having a petticoat of less diameter than said lining the 75 flange of the lining will be frictionally retained by said petticoat and whereby any pressure upon the top of the dome-shaped portion of the lining will cause a spreading of said flange and a tightening of its fit in 80 said petticoat.

JOSEPH KEEFE.
